UNITED STATES PATENT OFFICE.

CLARENCE S. BROOMHALL, OF SPENCERS STATION, OHIO.

SHIPPING-CRATE.

1,283,648.

Specification of Letters Patent.

Patented Nov. 5, 1918.

Application filed January 25, 1917. Serial No. 144,506.

To all whom it may concern:

Be it known that I, CLARENCE S. BROOMHALL, a citizen of the United States, residing at Spencers Station, in the county of 5 Guernsey and State of Ohio, have invented new and useful Improvements in Shipping-Crates, of which the following is a specification.

This invention relates to shipping crates 10 and more particularly to shipping cases for sending eggs and like articles by parcel post.

The principal object of the invention is to provide a simple, cheaply constructed, durable and conveniently set up device of this 15 character which also embodies novel, simple and efficient connecting means for the parts.

Further objects of the invention will appear as the following description is read in 20 connection with the accompanying drawing, which forms a part of this application, and in which:—

Figure 1 is a perspective view.

Fig. 2 is a plan view of the blank.

25 Fig. 3 is a sectional view showing the filler cage arranged within the case.

Referring more particularly to the drawing, the case is constructed of a single piece of material and comprises a bottom 1, top 2 30 and sides 3 and 4, and ends 5 and 6, respectively. The bottom is folded on the line 7 to produce the side 3 and upon the opposite side as at 8 to produce the side 4 and top 2, this part being folded upon the line 9 so that 35 the top may be carried over parallel with the bottom, as shown in Fig. 1. At the marginal edge of the top there is formed an integral flap 10 which may be secured to the free, outer or upper edge of the side 3. Each 40 of the ends 5 and 6 have formed integral therewith the flaps 11 which reinforce the corners when the box is folded and both preferably have flaps as indicated at 12 to reinforce the upper edges. Secured to the

bottom and extending transversely across the 45 same is a reinforcing wire 13 having loops 14 in its ends to connect with the hooks formed on the wires 15. The wires 15 are secured to the ends 5 and 6 by means of strips of paper or fabric and have formed at 50 their upper ends the loops 16 to engage with the hooks 17 formed at the terminals of the wire 18 extending across the top.

Removably mounted within the case is an egg nest of ordinary form preferably constructed of wire and made collapsible so that it may be folded when removed and so that when the eggs are placed therein the compartments may be completely filled with saw dust, shavings or similar material. 60

What is claimed is:—

A receptacle comprising a blank including a bottom member, a side member connected therewith, a second side member at the opposite side of the bottom member, a top connected with the second side member, a flap extending from the top, means for securing the flap to the side member first named to form a closure having oppositely located sides, a top and a bottom, with two open ends, detachable means for closing the ends, said means extending across the top and bottom and across both of the end members thereby inclosing the receptacle, and comprising a plurality of jointed members, and strips of 75 flexible material covering the respective jointed members and having their ends terminating at a slight distance from the joints thereof, said flexible strips connecting the jointed members respectively with the top, 80 the ends and the bottom of the receptacle, leaving the jointed portions unobstructed.

In testimony whereof I affix my signature in presence of a witness.

CLARENCE S. BROOMHALL.
